Des. 218,102
Patented July 21, 1970

218,102

REMOTE STARTER SWITCH

Edwin L. Schwartz, Los Angeles, Calif., assignor to Rite Autotronics Corporation, Los Angeles, Calif., a corporation of California

Filed June 12, 1969, Ser. No. 17,674

Term of patent 14 years

Int. Cl. D13—03

U.S. Cl. D26—13

Fig.1

Fig.3

Fig.2

Fig.4

Fig.5

FIG. 1 is a perspective view of the remote starter switch showing my new design;

FIG. 2 is a side elevational view taken from the back side of FIG. 1;

FIG. 3 is a side elevational view taken from either side of FIG. 2;

FIG. 4 is a plan view taken from the top of FIG. 3;
FIG. 5 is a plan view taken from the bottom of FIG. 3.

I claim:

The ornamental design for a remote starter switch, substantially as shown.
